J. P. RATIGAN

BAIL CONSTRUCTION FOR GRIPS AND THE LIKE

Original Filed June 21, 1924

Patented Dec. 1, 1925.

1,563,657

UNITED STATES PATENT OFFICE.

JAMES P. RATIGAN, OF WALNUT PARK, CALIFORNIA.

BAIL CONSTRUCTION FOR GRIPS AND THE LIKE.

Original application filed June 21, 1924, Serial No. 721,607. Divided and this application filed April 20, 1925. Serial No. 24,648.

To all whom it may concern:

Be it known that I, JAMES P. RATIGAN, a citizen of the United States, residing at Walnut Park, in the county of Los Angeles and State of California, have invented a new and useful Bail Construction for Grips and the like, of which the following is a specification.

This invention relates to bail constructions of the character employed, for example, on elevators, grips and clamps of the type used in the art relating to the drilling and pumping of oil wells, and this application is a division of my former application for patent for grip, Serial No. 721,607, filed June 21, 1924.

One of the important objects of the invention is to provide for quick attaching and detaching of the bail.

20 A further object is to provide a construction in which the bail members are loosely hooked into the body that is supported by said members.

25 A further object is to provide a bail construction that is essentially simple and inexpensive to manufacture.

The accompanying drawings illustrate the invention:

30 Fig. 1 is a plan view of a bail construction embodying the invention, the invention being embodied in a grip of the character employed for holding a sucker rod, which is shown in cross section.

35 Fig. 2 is an elevation, mainly in section, on the line indicated by 2—2, Fig. 1.

Fig. 3 is a sectional elevation on the line indicated by 3—3 of Fig. 1.

Referring to the drawings, there is provided, in this instance, an elongate angular body 11 having in one side a recess 12, the inner wall of which is concave. The recess 12 will accommodate several sizes of sucker rods or polish rods, one being indicated in cross section at *a* within the recess 12. A vertical plane passing longitudinally of the body 11 through the axis of the recess 12 coincides with the axes of openings 13 formed in the respective ends of the body 11 and opening, respectively, into cavities 14, 15, in said body.

40 Hook-shape links or bail members 16 extend through the openings 13, the tips of said links being accommodated in the cavities 14, 15, respectively. The hook-shape of the links 16 tends to prevent said hooks

pulling out of the openings 13, and it may be desirable in some instances to further insure against such pulling out by the provision adjacent to the tips of the links of transversely extending cotter pins 17 which prevent withdrawal of the links 16 by bearing against the outer end walls of the cavities 14, 15.

45 Suspension cables 18 are secured to the links 16 by any of the usual means or in any customary manner. The openings 13 are approximately at equal distances from the axis of the recess 12 and, accordingly, the body 11 will be nicely balanced upon the links 16 when the weight of the sucker rods or other members that are to be clamped to the body is imposed thereon. Any suitable clamping member 19 is thrust against the polish rod *a* by a screw 20 or any other suitable means, and it is understood that the 50 particular construction of the body 11, clamping member 19 and means 20 for actuating the clamping member, as illustrated in the drawings, is merely illustrative of a clamping construction that may be supported by the bail members 16.

55 The upper walls of the openings 13 constitute downwardly projecting shoulders 21, against which the upward curved tips 22 of the member 16 would tend to strike if the cotter pins 17 were omitted, because the tips of the bail members are above the level of said shoulders and, thus, it will be understood that even if the cotter pins were omitted, the member 16 would not become detached accidentally from the body 11 by movement of the member 16 straight away from the body 11. Even though the cotter pins 17 were omitted, it would be necessary, in order to detach either member 16, to swing the upper end of said member inwardly toward the axis of the body 11 in order to cause the tip 22 of the member 16 to lower sufficiently so that it will pass by the shoulder 21 and through the opening 13. This 60 makes it clear that, in reality, no strain comes upon the cotter pins 17, that said cotter pins may be omitted, if desired, and that their principal function is to prevent the members 16 from becoming accidentally 65 detached from the body 11 when the grip is not in use.

70 It will be understood from the foregoing that, to use the invention, the body 11 will be suspended by the bail members 16 and 75

cables 18 from the usual hoisting tackle and that the body 11 will then be secured to the sucker rod or polish rod by operating the screw 20. The tackle will then be operated 5 to raise or lower the grip in a manner well understood in the art relating to the pumping of oil wells.

It is to be understood that the bail members 16 take different shapes and that those 10 shown in the drawings and above described constitute one form of suspension members that may be employed, and that the tips 22 constitute laterally extending shoulders engaging the upper walls of the cavities 14, 15 15 above the level of said shoulders.

I claim:

1. A bail construction for grips and the like, comprising a body having cavities near its opposite ends and openings communicating with the cavities, hook-shape links projecting through the openings, the tips of said links extending into the cavities, and suspension cables secured to the links and permitting of independent canting of the links 25 in the operations of attaching and detaching said links.

2. A bail construction for grips and the like, comprising a body having cavities near its opposite ends and openings communicat-

ing with the cavities, there being shoulders 30 projecting downwardly from the inner faces of the walls of the cavities, hook-shape bail members extending through the openings and into the cavities, the tips of the bails being above the level of the shoulders, and suspension cables secured to the links and permitting of independent canting of the links in the operations of attaching and detaching said links.

3. A bail construction for grips and the like, comprising a body having cavities near its opposite ends and openings communicating with the cavities, there being shoulders 40 projecting downwardly from the inner faces of the walls of the cavities, suspension members extending through the openings and into the cavities, said suspension members having laterally extending shoulders engaging the upper walls of the cavities above the level 45 of the shoulders, and cables secured to the suspension members and permitting of independent canting of said members in the operations of attaching and detaching said members.

Signed at Los Angeles, California, this 55
13th day of April, 1925.

JAMES P. RATIGAN.
